VALVE FOR INFLATABLE ARTICLES

Ward E. Roedding, Grand Rapids, Mich., assignor, by mesne assignments, to Van Cleef Bros., Chicago, Ill., a partnership consisting of Noah Van Cleef, Felix Van Cleef, Maxime Van Cleef, and Paul Van Cleef

Application November 9, 1931, Serial No. 573,939

7 Claims. (Cl. 273—65)

This invention relates to a valve and more definitely to a filling and sealing device adapted to be applied to a hollow play ball or the like whereby the same may be inflated and deflated at will.

Briefly described, my novel valve structure consists of a tapered pocket having a curved slit and a small opening near its wide end, this pocket being formed between the ball itself and a fabric covering located interiorly thereof. A collapsible tube extends outwardly through the fabric member and the small opening and air is introduced through this tube to inflate the ball. After inflation the tube is pulled inwardly through the opening by the person inflating the ball and is then folded and pushed into the narrow end of the tapered pocket where it is held in a pinched or clamped condition and is thus closed against the passage of air therethrough. A yielding member is located between the ball and the outer side of the fabric strip to reinforce the same and a similar member lies at the inner side of the fabric strip for the same purpose.

One advantage resulting from the novel structure set forth resides in the tapered pocket whereby access is readily had at the wider end thereof and by way of the curved slit for the purpose of pulling the tube inwardly through the opening and pushing it into the narrower portion of the pocket, the narrower portion of the pocket exerting more pressure upon the tube and hence holding the same in a tightly closed position, thereby keeping the ball in a properly inflated condition.

A second advantage of my invention is that the folded tube is located in centered position with respect to the sides of the tapered pocket and with the return bend at the bottom of the pocket whereby there is very little chance against its accidental displacement.

A third feature of my valve structure lies in the provision of an inelastic member at the inner side of the pocket. This member tends to hold the pocket in a closed position and hence prevents the curved slit therein from gaping open as it is very prone to do.

Fourthly, I provide a curved slit as distinguished from a straight slit as I have experimentally found that the former maintains a closed position much better than the latter.

Fifthly, I have also determined by experiment that by the use of an elastic immediately inside the rubber covering of the ball, whereby the fabric is located interiorly thereof and by then placing a second or inner yieldable member on

the inner side of the fabric that the shape of the pocket is retained to an exceptional degree.

Further advantages and features of the valve structure will become apparent upon an understanding of the following description.

Fig. 1 of the drawing is a fragmentary outside view of a rubber ball having a valve structure embodying the invention.

Fig. 2 is an inside view of the parts shown in Figure 1.

Fig. 3 is a sectional view taken on the line 3—3 of Fig. 1.

Fig. 4 is a sectional view similar to Fig. 3 but illustrating the manner in which the collapsible tube is forced together and pushed into the narrower portion of the pocket.

Fig. 5 is a sectional view showing the collapsible tube in a sealed or closed position, the ball having been inflated previously thereto.

In the drawing, I have shown a portion of a hollow play ball which comprises an elastic rubber casing 10 and a collapsible rubber tube 13 for inflating and deflating the casing. The casing 10 has a curved slit 11 and an opening 12 therethrough. The slit is for the purpose of inserting a foreign member, such as one's finger, to push the collapsible tube inwardly as shown in Fig. 3, and has circular holes at its ends so as to facilitate insertion of the foreign member or finger. The opening 12 is adapted to receive the tube 13 to hold it in a position whereby the ball may be inflated. See Fig. 3.

A gum or rubber member 14 is attached as by vulcanizing to the flap of the ball, that is, the portion of the casing 10 which has the curved slit 11 and the opening 12, and this member serves to reinforce the flap of the ball. The slit 11 and the opening 12 extend through the member 14 as clearly shown in Fig. 4.

A non-porous fabric member 15, of the shape shown in Fig. 2, is attached at its periphery to the inner side of the ball casing 10 and hence a pocket 16, see Figs. 4 and 5, is formed. Entry to this pocket is through the slit 11.

A rubber or gum member 17, see Fig. 2, fits against and is attached to the inner side of the fabric member 15 and a smaller member 18 is attached to the inner side of the member 17. The inner end of the tube 13 extends through a hole in the member 17 and is flared outwardly so as to form a flange-like part which is held between and is cemented or otherwise secured to the contiguous faces of the members 17 and 18. A hole is formed in the central portion of the member 18 in registry with the inner end of the tube 13 so

that the latter communicates with the interior of the casing 10 of the ball.

The operation is readily apparent. Before inflation the several elements are positioned as shown in Fig. 3 and after air or gas has been introduced through the tube 13, a foreign element 20, such as one's finger, see Fig. 4, is inserted through the slit 11 and is used to pull the tube inwardly through the opening 12 and to push the tube into the narrow end of the pocket 16. Next, the element 20 is withdrawn and the several parts assume the position shown in Fig. 5 thus holding the air against escaping from the ball.

Deflation of the ball is had by pulling out the tube 13 either through the slit 11 or the opening 12 whereupon the air escapes therethrough.

Having thus described my invention, I desire to protect the same by Letters Patent and claim:—

20. 1. As a new article of manufacture, an inflatable ball or the like comprising a casing formed of flexible material and having an additional layer of flexible material over a restricted area, a member located inside of the two layers and fastened thereto only at its periphery so as to form a pocket, said two layers having a curved slit extending therethrough at a point near the periphery of the member and also having an opening adjacent to said curved slit and positioned inwardly from the slit with respect to the periphery of the member, and a collapsible tube fastened to the inner side of said member at a point oppositely positioned to the said opening and adapted to extend outwardly through said opening for ball inflating purposes, said slit being adapted to be manually opened so that the flexible tube may be collapsed by pushing thereagainst with a foreign element inserted through said slit to seal the same in the manner described.
40. 2. An inflatable article as set forth in claim 1 in which the pocket has a relatively wide end and the slit and opening are located adjacent to said wide end of the pocket for the purpose described.
45. 3. An inflatable article of the class described comprising, a hollow body having an elastic wall, an elastic reinforcing portion of relatively small dimensions fastened to the inner side of said wall, said reinforced portion of said wall having a slit cut therethrough, a fabric member fastened to the inner side of the article at its reinforced portion whereby a pocket is formed therebetween, said slit forming a means of entrance to said pocket, an elastic member secured to the inner face of the fabric member, and a collapsible tube secured to the inner face of the elastic member and extending outwardly therethrough and through said pocket, said tube being adapted to be folded and forced into said pocket, said fabric being non-yieldable relatively to the elastic parts of the article and also being of non-perforate construction except for the small hole therethrough to permit the collapsible tube to extend therethrough.
65. 4. An inflatable article comprising a casing of elastic material, a comparatively small piece of non-porous, substantially inelastic material secured marginally to the inner face of the casing and defining a pocket, said casing having a slit near the margin of the pocket-forming piece to provide access to the pocket and also having an opening at the side of the slit nearer the central portion of the pocket, and a collapsible tube for

use in inflating the article extending through, and attached to, the pocket-forming piece at a point in registry with the aforesaid opening, said tube being adapted to extend through the opening during inflation of the article and being further adapted to be withdrawn from the opening and doubled over by an element inserted into the pocket through the slit and to be pushed by such element into the portion of the pocket remote from the slit where it is held in a collapsed condition and prevents deflation of the article.

5. An inflatable article of the character described, comprising a casing of elastic material, a tapered piece of non-porous, substantially inelastic material secured marginally to the inner face of the casing and defining a tapered pocket, said casing having a slit therethrough adjacent the wide end of the pocket to provide access to said pocket and also having an opening at the side of the slit near the central portion of the pocket, and a collapsible tube for use in inflating the article extending through, and attached to, the pocket forming piece at a point in registry with the aforesaid opening, said tube being adapted to extend through the opening during inflation of the article and being further adapted to be withdrawn from the opening and doubled over by way of an element inserted into the pocket through the slit and to be pushed by such element into the small end of the pocket where it is held in a collapsed condition and prevents deflation of the article.

6. An inflatable article of the character described comprising a casing of elastic material, a comparatively small, tapered piece of non-porous, substantially inelastic material secured marginally to the inner face of the casing and defining a pocket, said casing, for the purpose of providing access to the pocket, having extending therethrough adjacent to the wide end of the pocket a slit with the ends thereof curved in the direction of the narrow end of the pocket, and a collapsible tube for use in inflating the article extending through, and attached to, the pocket-forming piece in off-centered relation with respect to the slit and adapted after inflation of the article to be doubled over by an element inserted into the pocket through the slit and to be pushed by said element into the narrow end of the pocket where it is held in a collapsed condition and prevents deflation of the article.

7. An inflatable article of the character described comprising a casing of elastic material, a comparatively small, tapered piece of non-porous material secured marginally to the inner face of the casing and defining a pocket, said casing, for the purpose of providing access to the pocket, having extending therethrough adjacent to the wide end of the pocket a slit with the ends thereof curved in the direction of the narrow end of the pocket, and terminating in comparatively small circular holes, and a collapsible tube for use in inflating the article extending through, and attached to, the pocket-forming piece in off-centered relation with respect to the slit and adapted after inflation of the article to be doubled over by an element inserted into the pocket through the slit and to be pushed by said element into the narrow end of the pocket where it is held in a collapsed condition and prevents deflation of the article.

WARD E. ROEDDING.
